UNITED STATES PATENT OFFICE.

IRVING KLINDT, OF ROUND MOUNTAIN, NEVADA.

CONCENTRATING-TABLE.

1,360,764.

Specification of Letters Patent. Patented Nov. 30, 1920.

Application filed February 19, 1920. Serial No. 359,993.

To all whom it may concern:

Be it known that I, IRVING KLINDT, a citizen of the United States, residing at Round Mountain, in the county of Nye and State 5 of Nevada, have invented a new and useful Concentrating-Table, of which the following is a specification.

My invention relates to concentrating machines and is more particularly directed to 10 the type of machines known as wet concentrators and which are especially adaptable for the treatment of ore pulps and slimes.

The object of the invention is to provide a horizontal concentrating table of shallow 15 box form and to longitudinally reciprocate the table to cause a stratification of the pulp and the discharge of the tailings in a plane transverse to the direction of reciprocation.

Another object is to provide a concentrating 20 table combined with means for feeding the ore pulp along the longitudinal center of the table and directing it transversely to the direction of reciprocation of the table, the longitudinal reciprocation of the table 25 causing the heavier mineral values to form a lower strata on the table surface where they discharge into a longitudinal concentrate trough in the center of the table surface, and causing the lighter tailings to be 30 discharged over the side boards of the table in a direction transverse to the direction of reciprocation of the table.

A further object is to provide a concentrating 35 table reciprocated in a substantially horizontal plane and in which the pulp bed is continuously maintained in a level plane, said table having a concentrate slot or trough extending in a plane parallel to the direction of reciprocation.

40 Another object is to provide a concentrating table in which the pulp bed is maintained in a level plane and the pulp is fed along the longitudinal center of the table and parallel to its direction of reciprocation, and 45 is directed transversely beneath the surface of the pulp bed.

Various other objects and advantages will 50 be more fully apparent from the following description of the accompanying drawings, which form a part of this disclosure, and which illustrate a preferred form of embodiment of the invention.

Of the drawings:

Figure 1 is a side elevation of my improved concentrator.

Fig. 2 is a top plan view.

Fig. 3 is a top plan view with the feed trough removed.

Fig. 4 is a longitudinal vertical section.

Fig. 5 is an end elevation.

Fig. 6 is an enlarged transverse section illustrating the separation of the ore pulp.

In the drawings, A designates the concentrator table which is supported upon vertical legs B, the legs being attached to the under surface of the table and to the base 1 of the machine, by angled brackets 2. The legs are formed of flexible metal or wood to permit a relatively slight longitudinal reciprocation of the table and at the same 65 time are transversely rigid to prevent any side motion thereof.

The table A is given a reciprocating movement, longitudinally, by any suitable operating mechanism, such as, by means of an 70 eccentric link device, as indicated at 3.

The table is of shallow box form having a table surface 4 which is substantially level, longitudinally, and which is slightly inclined downwardly and inwardly to a medial concentrate slot 5 which extends parallel to the direction of table reciprocation. Discharge spigots 6, by which the discharge of the concentrate from the slot is regulated, communicate with the concentrate slot and are 75 adapted to discharge the concentrate into a stationary concentrate launder C which is supported beneath and in longitudinal alignment with the spigots, and is slightly inclined to direct the flow of the concentrate 80 toward one end of the machine.

The side boards 7-8 of the table A extend upwardly a distance commensurate to the depth to which it is desired to maintain the pulp bed. The end boards 9, 10 extend 85 upwardly to a greater height than the side boards and the adjacent portions of the side boards are inclined upwardly to the height of the end boards, as indicated at 11, 11. This provides a table having higher 90 marginal walls at its opposed ends, and the purpose of this structure is to prevent the ore pulp being thrown or washed over the table ends by the sudden changes in table movements. Each of the side boards 7, 8 100 extend below the bottom of the table and into stationary tailings launders D-D which are slightly inclined in a direction in which it is desired that the tailings shall be 105 discharged.

The feed trough E is longitudinally extended the length of the concentrator table,

- above the concentrate slot 5, and rests upon and is attached to the end boards 9—10 of the table. In the lower portions of the sides of said feed trough are provided series of discharge orifices 12—12 through which the ore pulp is fed to the table and secured to the trough, as by means of bolts 13, and suitably spaced from the trough are opposed baffle plates 14—14 which extend longitudinally the full length of the table and vertically above the discharge orifices 12—12 and downwardly below the horizontal level of the pulp bed on the table and below the tops of the table side boards 7—8.
- 15 It will be evident from the above, that the feed trough E and the table A, and connected parts, will be reciprocated as a unit in a longitudinal direction and in a substantially level plane.
- 20 In operation, the ore pulp or slime will flow through the discharge orifices 12—12 and against the baffle plates 14—14 which will direct the pulp downwardly beneath the surface of the pulp bed on the table, as indicated by the arrows 15—15 in Fig. 6. This flow of the pulp is assisted by the reciprocation of the table which also serves to maintain the pulp in the feed trough in an agitated state to prevent a separation in said trough and to prevent a clogging of the discharge orifices 12—12.

The reciprocation of the table causes a stratification of the pulp bed, the heavier mineral values sinking to the table surface, as indicated by the arrows 16—16 and gradually working into the concentrate slot 5, and the lighter gangue flowing transversely across the table and overflowing over the table side boards 7—8 and into the 40 tailings launders D—D as indicated by the arrows 17—17 in Fig. 6.

The spigots 6 may be regulated to continuously discharge the concentrate into the concentrate launder C and they may be 45 opened at intervals for an intermittent discharge.

If desired, the concentrate slot 5 may be eliminated and the spigots 6 connected directly into the bottom of the table and in a 50 concentrator proportioned to maintain a relatively deep pulp bed, the table surface may be transversely level.

With the above described construction I have produced a concentrator adapted to 55 float a bed of ore pulp or slime and by reciprocating the table longitudinally in a level plane I cause a stratification of the pulp and a continuous separation by which the mineral values seek the longitudinal 60 center of the table and the gangue is directed transversely relative to the direction of reciprocation and overflows the side boards of the table.

I claim:

- 65 1. In a concentrator of the character de-

scribed, a horizontal concentrator table of box form having imperforate side and end walls and a floor having no longitudinal pitch, said table holding a floating bed of ore pulp, means discharging ore pulp along the longitudinal center of the table, means supporting the table in a level plane, and means for longitudinally reciprocating the table in a substantially horizontal plane to cause the mineral values to collect along the longitudinal center of the table and the tailings to flow in opposite transverse directions and overflow the side walls of the table.

2. In a concentrator of the character described, a horizontal concentrator table of box form having imperforate side and end walls, a floor having no longitudinal pitch and a longitudinal medial concentrate groove, said table holding a floating bed of ore pulp, means discharging ore pulp into the pulp bed above the concentrate groove, means supporting the table in a level plane, and means for longitudinally reciprocating the table in a substantially horizontal plane to cause the mineral values to collect in the concentrate groove and the tailings to flow in opposite transverse directions and overflow the side walls of the table.

3. In a concentrator of the character described, a horizontal concentrator table of box form having imperforate side and end walls and a floor having no longitudinal pitch, said table holding a floating bed of ore pulp, feeding means carried by the table and discharging ore pulp along the longitudinal center of the table, means supporting the table in a level plane, and means for longitudinally reciprocating the table in a substantially horizontal plane to cause the mineral values to collect along the longitudinal center of the table and the tailings to flow in opposite transverse directions and overflow the side walls of the table.

4. In a concentrator of the character described, a horizontal concentrator table of box form having imperforate side and end walls and a floor having no longitudinal pitch, said table holding a floating body of ore pulp, feeding means discharging ore pulp along the longitudinal center of the table, means supporting the table in a level plane for longitudinal reciprocation and against transverse movement, and means for longitudinally reciprocating the table in a substantially horizontal plane to cause the mineral values to collect along the longitudinal center of the table and the tailings to overflow the opposite side walls of the table.

5. In a concentrator of the character described, a concentrating table of box form having imperforate side and end walls and a floor having no longitudinal pitch, said table holding a floating bed of ore pulp,

means for feeding ore pulp along the longitudinal center of the table, means causing the pulp to flow beneath the surface of the pulp bed as it is fed to the table, and means 5 for reciprocating the table in a substantially horizontal plane.

6. In a concentrator of the character described, a rectangular concentrating table of box form having imperforate side and end 10 walls and a floor having no longitudinal pitch and provided with a longitudinal medial concentrate groove closed at both ends, means supporting the table for longitudinal reciprocation and against transverse movement, and means for reciprocating the table 15 to cause the mineral values to separate from the tailings and collect in the concentrate groove, and to cause the tailings to overflow the side boards of the table in a direction 20 transverse to the direction of reciprocation.

7. A concentrator of the character described, a rectangular concentrating table of box form having imperforate side and end walls and a floor having no longitudinal 25 pitch, said table holding a floating bed of ore pulp, feeding means extending lengthwise of the table and adapted to discharge ore pulp along the medial portion of the table, baffle plates adjacent the feeding 30 means for compelling the feed pulp to flow beneath the surface of the pulp bed, and means for longitudinally reciprocating the table.

8. In a concentrator of the character described, a concentrating table of box form having imperforate side and end walls and a floor having no longitudinal pitch, said table holding a floating bed of ore pulp, a feed device above the longitudinal medial 35 portion of the table and having discharge orifices above the ore bed surface, a baffle plate extending below the ore bed surface and positioned adjacent the discharge orifices for directing the flow of ore pulp therefrom, and means for reciprocating the table 40 to cause a separation of the mineral values from the tailings and to cause the tailings to overflow the table sides.

9. In a concentrator of the character described, a rectangular concentrating table of box form having imperforate side and end walls and a floor having no longitudinal 45

pitch, said table holding a floating bed of ore pulp, the surface of the table throughout its length being slightly inclined downwardly 55 and transversely to its longitudinal center, means for longitudinally reciprocating the table to cause the mineral values to collect at the longitudinal center thereof and the tailings to overflow the table sides, and means 60 positioned along the longitudinal center of the table for discharging the mineral values.

10. In a concentrator of the character described, a rectangular concentrating table of box form for holding a floating bed of ore 65 pulp, and having a medial longitudinal concentrate groove, with the table surface inclined transversely and downwardly to the groove, means supporting the table for longitudinal reciprocation and against trans- 70 verse movement, a feed trough carried by the table and positioned above and parallel to the concentrate groove, said trough having longitudinally disposed discharge orifices, baffle means adjacent the discharge 75 orifices for directing the feed pulp beneath the surface of the pulp bed, and means for longitudinally reciprocating the table to cause a separation of the mineral values from the tailings and a collecting of the 80 mineral values in the concentrate groove and to cause the tailings to overflow the table sides, and means communicating with the concentrate groove to discharge the mineral values.

11. In a concentrator of the character described, a horizontal concentrator table of box form having imperforate side and end walls and holding a floating bed of ore pulp, feeding means discharging ore pulp along 85 the longitudinal center of the table, and means longitudinally reciprocating the table in a substantially horizontal plane to cause the mineral values to collect on the table at the point of feed discharge and the tailings 90 to flow in opposite transverse directions and overflow the side walls of the table.

Signed at Round Mountain, Nev., this 9th day of Feb. 1920.

IRVING KLINDT.
